Primary Examiner—Martie K. Holtje*Attorney, Agent, or Firm*—Finnegan, Henderson, Farabow, Garrett & Dunner, L.L.P.[57] **CLAIM**

The ornamental design for a binder cover, as shown and described.

DESCRIPTION

FIG. 1 is a perspective view of a binder cover embodying my new design;

FIG. 2 is a top plan view thereof, the bottom plan view being a mirror image thereof;

FIG. 3 is a front elevational view thereof;

FIG. 4 is a right side elevational view thereof;

FIG. 5 is a rear elevational view thereof;

FIG. 6 is a left side elevational view thereof; and,

FIG. 7 is an enlarged cross-sectional view of the surface thereof taken along line 7—7 in FIG. 2.
